[57] CLAIM

The ornamental design for a jacket insulation for protecting damaged telephone conductors, substantially as shown and described.

DESCRIPTION

FIG. 1 is a plan view of the design of the jacket insulation for protecting damaged telephone conductors of the present invention;

FIG. 2 is a bottom view of the design of the jacket insulation for protecting damaged telephone conductors of the present invention;

FIG. 3 is a side view of the design of the jacket insulation for protecting damaged telephone conductors of the present invention;

FIG. 4 is a front, elevational view of the design of the jacket insulation for protecting damaged telephone conductors of the present invention; and

FIG. 5 is an isometric view of the design of the jacket insulation for protecting damaged telephone conductors of the present invention, one edge of the flexible jacket being shown in a deformed condition, said deformation permitting insertion of the conductors. The conductors per se are shown in broken lines for illustrative purposes only.
